UNITED STATES PATENT OFFICE.

LEE DE FOREST, OF NEW YORK, N. Y., ASSIGNOR TO DE FOREST RADIO TELEPHONE AND TELEGRAPH COMPANY, OF NEW YORK, N. Y., A CORPORATION OF DELAWARE.

OSCILLATING-CURRENT GENERATOR.

1,201,270.

Specification of Letters Patent. Patented Oct. 17, 1916.

Application filed September 14, 1914. Serial No. 861,711.

To all whom it may concern:

Be it known that I, LEE DE FOREST, a citizen of the United States, and residing at New York, in the county and State of New York, have made a certain new and useful Invention in Oscillating-Current Generators, of which the following is a specification.

This invention relates to oscillating current generators.

10 The object of the invention is to provide means which are simple and efficient for generating oscillating currents.

15 A further object of the invention is to increase the oscillation energy of currents generated.

Other objects of my invention will appear more fully hereinafter.

20 My invention consists substantially in the construction, combination, location, and relative arrangement of parts and circuits all as will be more fully hereinafter set forth, as shown by the accompanying drawing, and finally pointed out in the appended claims.

25 Referring to the drawing, Figure 1 shows an oscillating current generator embodying my invention as applied to a radiating antenna system. Fig. 2 shows a modified form of audion generator. Fig. 3 shows an arrangement employing a resistance connected 30 up in the circuit of the grid element of the audion.

In accordance with the principles of my invention, I propose to employ an audion 35 consisting of the usual wing, grid and filament elements inclosed within an evacuated vessel, and suitably associated circuits and current sources, to generate oscillating currents, and to increase the oscillation energy of the currents thus generated, by means 40 of a non-inductive resistance, or a non-inductive resistance and a capacity arranged in suitable relation to each other and to the circuits of the above mentioned audion elements.

45 Referring to the drawing, I have shown a form of audion generator and circuit connections therefor embodying the principles of my invention and wherein the audion consists of an evacuated vessel 3, in which are

50 inclosed the electrode members 4, 5, 6. The electrode member 4 I term the hot electrode, which, in this instance, is in the form of an incandescent body or filament. The electrode member 5, is in the form of cold plates,

preferably of metal, and I have found that 55 nickel plates well answer the desired purpose. The electrode member 6 is in the form of grids and of suitable material and formation. In the particular arrangement shown in Fig. 1, to which, however, my invention is not to be limited or restricted, I 60 employ two plates to form the electrode 5, and two grids to form the member 6, and preferably each grid is interposed in the space between the member 4 and a plate of 65 member 5.

In Fig. 2, I have shown as an embodiment of my invention, an audion in which a single grid 7 and a single plate 8, are employed, the grid being interposed between the plate and 70 the filament 9.

The incandescent body or filament 4, 9, may be supplied with current from any suitable or convenient source. I have shown a battery 10, 11 for this purpose. The current 75 supply in the circuit of the filament may be controlled in any suitable or convenient manner, as, for instance, by means of an adjustable rheostat or resistance indicated at 12.

Reference numeral 13 indicates a source of 80 E. M. F. preferably of high voltage, which may be regulated in any convenient manner by means of the adjustable switch or connection 14. The positive side of the source 13 of E. M. F. is connected through the adjustable connection 14 to the audion element or plate members 5, Fig. 1, or 8, Fig. 2. The negative side of the E. M. F. source is connected to one side of the circuit of filament 4, 9.

Reference numeral 15 indicates an inductance, one terminal of which is connected to the grid element 6, 7, of the audion, while the other terminal thereof is connected to the plate element 5, 8. Across the terminals of 95 the inductance 15 is connected a capacity, preferably adjustable, such, for instance, as the variable condenser 16, said inductance and condenser together with the audion forming an oscillating system. The inductance 15 should be so designed as to have a minimum damping effect and distributed capacity.

I have found that the presence of a permanent positive charge of electro-motive 105 force on the grid element of the audion reduces the intensity of the oscillations set up by the system. Therefore it is important

to effectually insulate the grid from the positive side of the electro-motive force source 13. To accomplish this I prefer to insert a "blocking" condenser 18, in the circuit connection of the inductance 15 with the grid element of the audion.

An audion system such as above described forms an oscillation generator of exceeding simplicity and wherein oscillations are generated in the system 5 (or 8), 15, 16, 18, 6 (or 7). I have discovered, however, that by connecting the audion grid system to one side of the current source 10 which supplies current to the filament, or to the negative 15 side of the flux or electro-motive force source 13, through a very high and preferably non-inductive resistance 19, the energy of the oscillations generated in the audion-inductance-capacity system is enormously increased, for example, from the order of a micro-watt to that of tens or hundreds of watts. The resistance 19 should be made adjustable, but its optimum value is not critical. I have also discovered that a still further increase in oscillation energy is obtained if a small capacity, such as a variable condenser 20 is connected in parallel to the resistance 19.

I am at present unable to offer a satisfactory scientific explanation of the action which takes place in a system such as I have described. I have discovered however by actual experience, that an enormous increase in oscillation energy is secured when the resistance 19, either alone or with the capacity 20 is employed and coupled up in the manner and relation set forth. In this connection I wish it to be understood that when I specify a resistance coupled up as shown and described, I wish to include also the use of a capacity coupled up in parallel thereto for the desired purpose.

Oscillations generated as above described may be utilized for any purpose for which they are adapted. I have shown the generating system associated with a radiating antenna system which, for illustrative purposes I have shown in the form of an aerial 21 connected to earth at 22, and with which 50 is inductively associated the oscillating system through the inductance 15, and coil 23, respectively forming the primary and secondary of a transformer the secondary 23 being included in the circuit of the antenna.

To attain the best results the radiating system should be in tune with the oscillating system.

Having now set forth the objects and nature of my invention and arrangement embodying the principles thereof, what I claim as new and useful and of my own invention is,

1. In an oscillation generator system, the combination with a normally oscillating

audion having three terminals, and a resistance connected between two of the terminals of said audion.

2. In an oscillation generator system, the combination with a normally oscillating audion, and a resistance connected between the elements of said audion, and a capacity connected in parallel to said resistance.

3. In an oscillation generator system, the combination with a normally oscillating audion, having three electrode members and a resistance connected between two of the electrode members.

4. In an oscillation generator system, the combination with a normally oscillating audion, having three electrode members and a resistance connected between two of the electrode members, and a capacity connected in parallel to said resistance.

5. In an oscillation generator system, the combination with a normally oscillating audion having three terminal elements and a non-inductive resistance connected between two of the elements of the audion.

6. In an oscillation generator system, the combination with a normally oscillating audion having three electrode members and a non-inductive resistance connected between two of the electrode members.

7. An oscillation generator system including an audion having plate, grid and filament elements, and circuit connections therefor, a resistance connected between the grid and filament members and an out-put circuit for the generated oscillations.

8. An oscillation generator system including an audion having plate, grid and filament elements, and circuit connections therefor, a non-inductive resistance connected between the grid and filament members and an out-put circuit for the generated oscillations.

9. An oscillation generator system including a work circuit, and means for feeding said work circuit including an audion having plate, grid and filament elements, and circuit connections therefor, and a resistance connected between the grid and filament members, and a capacity connected in parallel to the resistance.

10. An oscillation generator system including an audion having plate, grid and filament elements, an inductance having its terminals respectively connected to the grid and plate elements and constituting the out-put circuit for the generated oscillations, a capacity connected across said terminals, a source of electro-motive force for the plate element, a source of current supply for the filament, and means to insulate the grid element from said source of electro-motive force.

11. An oscillation generator system including an audion having plate, grid and filament elements, an inductance having its

- capacity connected across said terminals, a source of electro-motive force for the plate element, a source of current supply for the filament, and a "blocking" capacity in the terminal connection of the inductance and grid.
12. An oscillation generator system including an audion having plate, grid and filament elements, an inductance having its terminals respectively connected to the grid and plate elements and constituting the output circuit for the generated oscillations, a capacity connected across said terminals, a source of electro-motive force for the plate element, a source of current supply for the filament, and a "blocking" capacity in the terminal connection of the inductance and grid, and a resistance connecting the grid and filament.
13. An oscillation generator system including an audion having plate, grid and filament elements, an inductance having its terminals respectively connected to the grid and plate elements and constituting the output circuit for the generated oscillations, a capacity connected across said terminals, a source of electro-motive force for the plate element, a source of current supply for the
- and filament, and a capacity in parallel to the resistance.
14. An oscillation generator system including an audion having plate and grid elements, and a heated element, and a resistance connected at its terminals directly to the grid and heated element.
15. An oscillation generator system including an evacuated vessel, cold electrodes and a heated electrode inclosed therein, and an external resistance connected at its terminals directly to the heated and one of the cold electrodes.
16. An oscillation generator system including an audion having plate and grid elements and a heated element, and a resistance connected at its terminals directly to the grid and heated element and a capacity connected in parallel to said resistance.
- In testimony whereof I have hereunto set my hand in the presence of the subscribing witnesses, on this 11th day of September A. D., 1914.

DISCLAIMER.

1,201,270.—*Lee de Forest*, New York, N. Y. OSCILLATING-CURRENT GENERATOR.
Patent dated October 17, 1916. Disclaimer filed December 29, 1922, by the
assignee, *De Forest Radio Telephone & Telegraph Company*.

Hereby enters this disclaimer to that part of the claim in said specification which
is in the following words, to wit:

“5. In an oscillation generator system, the combination with a normally oscillating
audion having three terminal elements and a non-inductive resistance connected
between two of the elements of the audion.

“6. In an oscillation generator system, the combination with a normally oscillating
audion having three electrode members and a non-inductive resistance connected
between two of the electrode members.”
